LUBRICATING DEVICE FOR MACHINE TOOLS

Arthur F. Bennett, West Barrington, R. I., assignor to Brown and Sharpe Manufacturing Company, a corporation of Rhode Island

Application November 10, 1937, Serial No. 173,851

13 Claims. (Cl. 90—21)

The present invention relates to improvements in lubricating devices for machine tools, and more particularly to means well adapted for lubricating certain moving parts of a milling machine of the general type having a longitudinally reciprocable work table, a transversely movable saddle support, and a vertically adjustable knee support.

It is an object of the present invention to provide a novel and improved lubrication system of the non-return type which is well adapted for supplying lubricant economically and efficiently to the various moving parts mounted in the saddle support and relatively movable work table of a milling machine.

More specifically, it is an object of the invention to provide a lubricating system of this general description which is well adapted to provide intermittent lubrication under pressure to the various moving parts at intervals which will bear a definite relation to the extent and character of the machine operation to provide an adequate but not excessive supply of lubricant to the operating parts.

With these and other objects in view, as may hereinafter appear, the several features of the invention consist in the devices, combinations and arrangement of parts hereinafter described and claimed, which together with the advantages to be obtained thereby will be readily understood by one skilled in the art from the following description taken in connection with the accompanying drawings, in which Fig. 1 is a detail view in front elevation of a milling machine illustrating particularly the reciprocable work table and transversely movable saddle support, and the lubricating devices supported thereon, only so much of the machine having been illustrated as is believed necessary to indicate the relation of the present invention thereto; Fig. 2 is a sectional view in front elevation taken through the work supporting table, and illustrating particularly portions of the table drive and certain of the connections for lubricating the parts of said drive; Fig. 3 is a plan view partly in section, taken on substantially the line 3—3 of Fig. 1, of applicant's lubricating system, the saddle support having been drawn in dot-and-dash lines to indicate the positions of the several parts of the lubricating system with relation thereto; Fig. 4 is a sectional view in left side elevation taken substantially on the line 4—4 of Fig. 1; Fig. 5 is a detail view in left side elevation and partly in section taken on the line 5—5 of Fig. 2, to illustrate certain of the driving and lubricating devices housed in the saddle support and table; Fig. 6 is a sectional view

in left side elevation taken on the line 6—6 of Fig. 3; Fig. 7 is a detail sectional view of the pump taken on the line 7—7 of Fig. 5; and Fig. 8 is a detail sectional plan view taken on the line 8—8 of Fig. 2.

The machine disclosed in the drawings, is a milling machine of the general type having a column designated generally at 10 in Fig. 4, on which is mounted a rotary milling cutter spindle which may be of ordinary description (not shown), a longitudinally reciprocable work table 12, a transversely movable saddle support 14 for the table, and a vertically adjustable knee 16. The table is slidably supported on ways 18 and 19 formed on a swivel mounting 15 which forms part of the saddle support 14 which is in turn slidably mounted for movement in a transverse direction on ways 20 on the knee 16.

The machine is also provided with conventional motion transmitting means for effecting either power or manual operation of each of the component parts of the work supporting assembly, including a main stem transmission mounted in the knee and branch transmissions therefrom for effecting relative movements of each of the table, saddle and knee supports. The driving connections referred to, will be hereinafter described only so far as is believed necessary to illustrate the application thereto of applicant's improved system for lubricating the moving parts carried by the saddle and table supports. Referring to Fig. 4, the power drive for each of the branch transmissions above referred to, is taken from a driving gear 24 and a drive shaft 26 which is rotatably supported in the knee to turn on a horizontal axis extending in a direction parallel to that of saddle support movement. The drive for the table 12 is taken from the shaft 26 through a branch transmission which comprises a vertically extending drive shaft 28 rotatably mounted in a casing 30 formed integrally with the saddle support 14. A bevel gear 32 secured to the lower end of the drive shaft 28, meshes with a gear 34 slidably mounted on the shaft 26, and keyed to turn therewith. The gear 34 is externally supported in a bearing 35 formed in the casing 30 which is arranged to support the gear 34 at all times in mesh with the cooperating gear 32. The vertical shaft 28 is connected through a starting, stopping and reversing clutch mechanism to a table drive shaft 36 rotatably mounted on and supported to move axially with the table. The shaft 36 in turn drives a table screw 38 also mounted on and supported against axial movement with relation to the table, and arranged to

mesh with a stationary nut 40 rigidly mounted on the saddle support 15. The driving connections thus briefly outlined, include a bevel driving gear 42 on the upper end of the drive shaft 28 which is arranged to mesh with and drive in opposite directions two bevel gears 44 and 45 which are loosely sleeved on the table shaft 36, and are supported respectively against endwise movement therewith by means of the external 10 bearings 46 and 47 on the saddle support. The bevel gear members 44 and 45 have formed thereon face clutch surfaces which are arranged for engagement with an intervening sleeve clutch member 48 which is keyed to rotate with the shaft 36, and to move axially thereon from the neutral position shown in Fig. 2, into clutching engagement with either of the oppositely driven gear members 44 or 45. The shaft 36, as best shown in Fig. 2 of the drawings, is supported at opposite ends in bearings 50 and 52, the screw shaft 38 being similarly supported at opposite ends in bearings 54 and 56 on the work supporting table. The screw shaft 38 is also rigidly supported against axial movement with relation to the table 12 by means of end thrust bearings 58 and 60 which are mounted between collars on the screw shaft 38 and opposite sides of a stationary lug 62 formed integrally with the table 12. The drive is taken from the drive shaft 36 to the feed screw 38 by means of an internal gear 64 mounted on a hand wheel 66 secured to the drive shaft 36, and arranged to mesh with a small pinion 68 secured to the end of the screw shaft 38.

The position of the clutch member 48 is readily 35 controlled through connections which include a forwardly extending rock shaft 70 (see Figs. 1 and 4) which is provided at its rear end with an offset pin 72 which engages in a shoe 74 mounted in a peripheral groove 76 in the clutch sleeve 48. 40 At its forward end the rock shaft 70 is provided with a manually operable reversing lever 78 which is moved in opposite directions from the intermediate neutral position shown, for example, in Fig. 1, to effect a drive of the table in opposite 45 directions. In order to provide for automatically stopping the table at the desired limit in its travel in either direction, table dogs 80 and 82 are adjustably mounted in a T-shaped slot 84 formed in the front side of the table 12 for engagement 50 respectively with two vertically arranged stop plungers 86 and 88 which are provided at their lower ends with rack teeth (see Fig. 3) for engagement with the opposite sides of a pinion 90 on the rock shaft 70. Actuation 55 of either of the plungers 86 or 88 by the cooperating dog will cause the shaft 70 and clutch member 48 controlled thereby to be returned to their intermediate neutral positions.

In accordance with the present invention, a 60 novel lubrication system is provided for supplying lubricant to the several bearing and other engaging parts of the driving mechanisms above described, which are mounted in the saddle and in the work table carried thereon. The system employed is of the non-return type in which lubricant drawn from a source of supply, is distributed to each of the parts needing lubrication in regulated amounts which are proportioned in accordance with the requirements of each part.

70 A feature of applicant's invention consists in the provision in a lubricating system of this general type, of means for supplying lubricant intermittently to the several parts needing lubrication, at intervals which depend upon and are determined by the extent to which these parts of the

machine are operated, so that the rate at which lubricant is supplied will be at all times substantially equal to the rate of consumption.

In the preferred form of applicant's lubrication system illustrated in the drawings, lubricant 5 is drawn from a reservoir carried in the saddle support, and is forced through a distributing system adapted for supplying lubricant in properly proportioned amounts to each of the operating parts by means of a pumping unit which is 10 rendered operative to force a carefully regulated amount of lubricant into the distributing system with each actuation of the reversing lever 78 of the machine above described.

As best shown in Figs. 3 to 6 inclusive, of the 15 drawings, a cylindrical chamber or reservoir 100 is provided in the saddle support 15 directly beneath one of the ways 19 for the table 12, from which lubricant is supplied to the moving parts 20 on the saddle and work supporting table. An oil filler plug 102 provides convenient means for replenishing the supply of lubricant to the reservoir when necessary. As best shown in Fig. 3 of the drawings, oil is drawn from the reservoir 25 through supply pipe 104 by means of a pump generally indicated at 106, which is mounted in the opposite side of the saddle support beneath the table way 18. Oil is forced from the pump 106 through a supply conduit 108 to a distributing head 110 which is supported, as best shown 30 in Figs. 3 to 6 of the drawings, at the right hand end of the saddle support, and beneath the reservoir 100. A pipe line 112 connected between the distributor head 110 and the reservoir 100 having 35 associated therewith a drip plug 114 provides an overflow connection for any excess oil forced into the distributor head 110 from the pump 106.

In order that oil may be supplied in properly proportioned amounts to the above operating 40 parts of the machine, a number of separate conduits 116, 118, 120, 122, 124, 126, 128 and 130 are provided from the distributing head 110, each of 45 which has provided therein a drip plug which is constructed to permit only the desired proportional part of the total supply of lubricant to be forced from the distributing head to the lubricated parts by the operation of the pump 106. As best 50 shown in Figs. 3 to 6 of the drawings, the conduits 116 and 128 are arranged to supply lubricant respectively to the table ways 18 and 19, the amount of lubricant supplied being regulated by 55 drip plugs 132 and 134 located respectively in the two conduits. The conduit 118 having therein a drip plug 136, as best shown in Figs. 2, 3 and 4, terminates at a point directly above the 55 table reversing clutch member 48, so that lubricant is permitted to drip downwardly onto the clutch collar 74 and into the peripheral groove 76 in the clutch sleeve 48, and thence into a well 60 formed by the recessed central portion of the bevel driving gear 42. From this point lubricant passes by gravity through ducts 138 formed in the gear 42, and a duct 140 in the vertically extending shaft 28, to lubricate the external bearing surfaces for these parts.

Lubricant is supplied from the distributing head 110 through the conduits 122 and 126 and drip plugs 142 and 144 connected therein to lubricate the external bearing supports 46 and 47 for the reversely driven clutch gear members 44 and 45. These conduits 122 and 126 are clearly illustrated in Figs. 2, 3 and 6 of the drawings.

The conduit 124 having a drip plug 148 associated therewith, is arranged to supply lubricant to the threads of the nut 40 which, as previously 75

set forth, is rigidly supported on the saddle support for engagement with the table feed screw 38. This conduit is best shown in Figs. 2, 3 and 6 of the drawings.

With the present construction, provision is made also for automatic lubrication of the bearings for the table drive shaft 36 and table screw 38 which are mounted on the work supporting table. The connections for lubricating these bearings comprise the two conduits 120 and 130 to which oil is supplied from the distributing head 110 through respective plugs 152 and 154. The conduit 120, as best shown in Figs. 1, 3 and 6, takes the form of a tube which extends upwardly 15 into a longitudinally extending slot or well 155 formed in the under side of the table 12 to provide clearance for the table screw 38 and stationary nut 40, and terminates directly above a trough 156 secured to and extending along one 20 of the upper corners of the well 155. The upwardly extending discharge end of the tube 120 is supported in a bracket 159 carried on the saddle support 15 (see Fig. 6). Oil collected in the trough 156, is drawn off through a conduit 25 160 (see Fig. 2) which leads to the bearing 56 for the feed screw 38 located at the right hand end of the table, and thence passes downwardly through a duct 161 to the bearing 52 for the table drive shaft 36. The conduit 130 is similarly arranged to supply oil to a trough 162 mounted in and extending along the opposite upper corner of the well 158 in the table 12. As best shown in Fig. 6, the discharge end of the conduit 130 takes the form of a vertically extending tube 35 which is supported in a bracket 163 on the saddle 15, and is provided at its upper end with an elbowed portion which terminates above the trough 162. Lubricant supplied to the trough 162 is distributed to two conduits 164 and 165 (see Fig. 8), the conduit 164 connecting with the end thrust bearings 58 and 60 for the table screw 38, and the conduit 165 connecting with the table screw bearing 54 at the left hand end of the table. From this point lubricant flows downwardly 40 through a duct 166 to the bearings 50 for the table drive shaft 36.

In accordance with the present invention, the pumping unit 106 previously referred to, is constructed and arranged to force a measured amount of lubricant from the reservoir 100 through the pipe connection 108 to the distributing head 110 at intervals which are automatically determined by the operation of the machine, the lubricant thus supplied under pressure being then distributed to the several operating parts in proportionate amounts as determined by the resistance valves of the drip plugs previously described, to insure an adequate but not excessive lubrication through each individual branch line. The pumping unit 106, as best shown in Figs. 3 and 7, comprises a casing having formed therein a central bore 170 adapted to receive a piston 172 and an actuating plunger 174. At its free end the plunger 174 is provided with a conically-shaped surface 176 for engagement with a V-shaped slot 178 formed in the rotatable shaft 70 which supports the reversing lever 78. A compression spring 180 coiled about the plunger 174 between a collar 182 secured to the plunger 174 and the abutting end of the pump casing 106, acts to force the plunger 174 and piston 172 to the right as shown in Figs. 1 and 3, to maintain an operative engagement between the plunger and the reversing lever shaft 70. With this construction of the parts, it will readily be seen that the movement

of the reversing lever 78 in either direction from its intermediate or neutral position, will cause the conical surface 176 to ride outwardly on the edges of the slot 178 to force the piston 172 to the left, and as the reversing lever 78 is returned to or passes through its intermediate position to cause the plunger to move again to the right under the pressure of the spring 180 to seat the conical portion 176 of the plunger in the bottom of the groove 178. As best shown in Fig. 7 of the drawings, an inlet 184 is provided in the side of the chamber 170, and is connected through an inlet check valve 186 with the pipe connection 104 from the reservoir 100. Lubricant is forced from the chamber 170 by the operation of the pump 10 through an outlet 188 and a check valve 190 to the pipe connection 108 leading to the distributing head 110. During the retracting movement of the piston 172 to the right, lubricant is drawn into the chamber 170 from the supply through check 20 valve 186, the outlet 188 being at this time shut off through the operation of the check valve 190. On the return stroke of the piston 172 to the left, the check valve 186 closes, and the check valve 190 opens causing lubricant to be forced 25 from the chamber 170 through the pipe line 108 to the distributing head 110.

It will be understood that the invention is not limited to the specific embodiment shown, and that various deviations may be made therefrom 30 without departing from the spirit and scope of the appended claims.

What is claimed is:

1. In a milling machine having a relatively stationary support, a movable support mounted 35 for reciprocable movement thereon, and motion transmitting means for the movable support including a reverser and a reversing lever therefor shiftable to determine the direction of support movement, a lubricating device which comprises 40 means for supplying lubricant under pressure including a distributing system through which lubricant is directed to said transmission means, and operating means actuatable upon each shift of the reversing lever for causing a limited quantity of lubricant to be forced from the supply into 45 the distributing system.

2. In a milling machine having a work supporting assembly including relatively movable table, saddle and knee supports, and motion transmitting means for said assembly having a plurality of associated moving parts including a table reverser mounted on the saddle, and a table reversing lever therefor shiftable to determine the direction of table movement, a lubricating device which comprises means for supplying lubricant under pressure to said parts including the reverser in the saddle, and operating means actuatable upon each shift of the reversing lever for causing a limited quantity of lubricant to be forced from the supply to said parts. 55

3. In a milling machine having a relatively stationary support, a movable support mounted for reciprocatory movement thereon, and motion transmitting means for the movable support having a plurality of associated moving parts, including a reverser and a reversing lever therefor, a lubricating device which comprises a source of lubricant supply, conduits through which lubricant is directed from the supply to lubricate said moving parts, a pump for forcing lubricant from the supply through said conduits, and means operative with each reversal of the reversing lever for actuating the pump to force a predetermined amount of lubricant through said conduits. 70 75

4. In a milling machine having a longitudinally reciprocable work table, a relatively stationary support for the work table, transmission means for the work table including driving and reversing connections and bearing supports therefor, a reversing lever on the stationary support having intermediate neutral and alternate driving positions, a lubricating device which comprises a source of lubricant supply, conduits through which lubricant is directed from the supply to lubricate the transmission, a pump for forcing lubricant through said conduits, and a connection operative upon movement of the lever in either direction from neutral position to actuate the pump.
5. In a milling machine having a longitudinally reciprocable work table, a relatively stationary support for the work table, transmission means for the work table including driving and reversing connections and bearing supports therefor, a reversing lever on the stationary support having intermediate neutral and alternate driving positions, a lubricating device which comprises a reservoir on said relatively stationary support, conduits through which lubricant is directed from the reservoir to lubricate the transmission, a pump having alternative draw and discharge strokes, and an actuating connection between the pump and lever whereby movement of the lever in either direction from neutral position operates to discharge lubricant through the conduits and the return movement of the lever to neutral position operates to draw lubricant from the reservoir.
6. In a milling machine having a longitudinally reciprocable work table, a relatively stationary support for the work table, and a table transmission having a plurality of associated moving parts including a reversing clutch, and bearing supports for said parts on the stationary support, a reversing lever on the stationary support for shifting the clutch, and a rotatable feed screw and bearing supports for the same on the table, a lubricating device which comprises a reservoir on the stationary support, conduits through which lubricant is directed from the reservoir to lubricate said bearings on the stationary and movable support, a pump for forcing lubricant from the supply through said conduits, and a connection from the reversing lever for actuating the pump to force a limited quantity of lubricant into said conduits with each shift of the lever.
7. In a milling machine having a relatively stationary support, a movable support mounted for reciprocatory movement thereon, transmission means for the movable support including a plurality of driving and reversing connections and bearing supports therefor, and a reversing lever for the movable support, a lubricating device which comprises a lubricant supply reservoir, a distributing head on the stationary support, a conduit through which lubricant is directed from the reservoir to the distributing head, branch conduits, and regulating means associated therewith for distributing proportional amounts of lubricant to different parts of said transmission, an additional branch conduit having regulating means therein for returning excess lubricant to the reservoir, a pump connected in said conduit between the reservoir and the distributing head, and a connection from the reversing lever for actuating the pump.
8. In a milling machine having a longitudinally reciprocable work table, a relatively sta-

tionary support for the work table, and table transmission means including a stationary nut, a rotatable feed screw and bearings for the feed screw on the table, said table having formed in the under side thereof a longitudinally extending well within which the feed screw and nut are mounted, a lubricating device which comprises a reservoir on the stationary support, a lubricant trough supported by the table within said well, a conduit therefrom through which lubricant is supplied to one of said feed screw bearings, a conduit on the stationary support through which lubricant is directed from the reservoir into said trough, a pump connected to force lubricant from the reservoir into said latter conduit, and means operative during machine operation for intermittently actuating the pump.

9. In a milling machine having a longitudinally reciprocable work table, a relatively stationary support for the work table, and transmission means for the table including a plurality of driving and reversing connections and bearing supports therefor on the stationary support, a rotatable feed screw and bearing supports therefor on the under side of the table, and a reversing lever mounted on the stationary support, a lubricating device which comprises a reservoir on the stationary support, a distributing head on the stationary support, a lubricant pump, and actuating connections from the reversing lever whereby movement of the reversing lever to either position will actuate the pump to force a predetermined amount of lubricant into the distributing head, branch conduits and regulating means therein through which lubricant is directed to lubricate said transmission means, a trough on the table extending longitudinally in the direction of table movement and a conduit therefrom for lubricating one of said feed screw bearings, and a branch conduit on said relatively stationary support and regulating means therein for supplying lubricant from the distributing head to the trough.

10. In a milling machine having a longitudinally reciprocable work table, a transversely movable saddle support for the work table, table transmission means including a nut fixed to the saddle support, a rotatable feed screw and bearings for the feed screw on the table, said table having formed on the under side thereof a longitudinally extending well within which the feed screw and nut are mounted, a table reversing lever mounted on the saddle, a lubricating device which comprises a reservoir on the saddle support, a pair of lubricant troughs supported by the table within said well, conduits from said troughs whereby lubricant is supplied by gravity respectively to the feed screw bearings, a pair of supply conduits on the stationary support through which lubricant is directed from the reservoir into each of said troughs, a pump connected to force lubricant from the reservoir into the supply conduits, and means for intermittently actuating the pump during machine operation.

11. In a milling machine having a longitudinally reciprocable work table, a transversely movable saddle support therefor, and table transmission means including a plurality of moving parts and a table feed reversing lever on the saddle, a lubricating device which comprises a reservoir in the saddle, a distributing head and connections therefrom for distributing lubricant to said moving parts, a pump connected between the reservoir and distributing head, and means operative with each reversal of the reversing le-

ver for actuating the pump to force a limited quantity of lubricant into the distributing head.

12. In a milling machine having a longitudinally reciprocable work table, a transversely movable saddle support for the work table, and table transmission means including a rotatable feed screw and bearings for the feed screw on the table, and a table reversing lever mounted on the saddle support, a lubricating device which comprises a reservoir on the saddle support, a distributing head on the saddle support, a connection therefrom for directing lubricant from the distributing head to said bearing on the table, a pump connected between the reservoir and distributing head, and a connection from the reversing lever for actuating the pump to force a limited quantity of lubricant into the distributing head with each reversal of the reversing lever.

13. In a milling machine having a longitudinally reciprocable work table, a transversely movable saddle support for the work table, and table transmission means having a plurality of associated moving parts including a reversing clutch and a driving nut supported within the stationary support, a reversing lever on the stationary support associated with the clutch, a feed screw and bearing supports for the same on the table, a lubricating device which comprises a reservoir on the stationary support, a pump, and conduits for distributing lubricant to said parts including the reversing clutch, driving nut and feed screw bearings, and a connection from the reversing lever for actuating the pump to force a limited quantity of lubricant into said conduits with each reversal of the lever. 5 10 15

ARTHUR F. BENNETT.
